TUNING INDICATOR SYSTEM FOR RADIO RECEIVING APPARATUS AND THE LIKE

George L. Beers, Haddonfield, N. J., assignor to Radio Corporation of America, a corporation of Delaware

Application July 31, 1937, Serial No. 156,676

4 Claims. (Cl. 250—20)

The present invention relates to tuning or resonance indicating means for radio receiving apparatus and the like, and more particularly tuning indication means which is adapted to provide resonance indication in comparison with a condition of nonresonance, whereby receiving apparatus provided with such indication means may be tuned more accurately than has heretofore been possible.

10 As is well known, in tuning radio receiving apparatus, it is desirable to tune exactly to resonance in order that the fidelity of reception may not be impaired, and, for this purpose, as a tuning aid, accurate visual means sharply responsive to a received signal is highly desirable.

Substantially all radio receiving apparatus is provided with automatic volume control means. As is well understood, automatic volume control devices tend to maintain the signal applied to the 20 second detector and therefore the volume or audio frequency output level substantially constant over an appreciable frequency range at each side of resonance, with the result that it is difficult to tune by ear a receiver having such a control. A 25 visual indicating device which responds to the signal amplitude at the second detector in such a receiver likewise cannot be used to give a satisfactory indication of resonance.

It is therefore a still further object of the present 30 invention to provide a tuning indication means for radio receiving systems having automatic volume control that shall give an accurate indication of resonance.

It is also a further object of the present invention to provide tuning indication means for radio receiving systems that shall give an indication of the direction in which the tuning elements thereof are to be adjusted to secure resonance with an incoming carrier wave or signal.

40 It may also be considered to be a further object of the invention to provide tuning indication means for radio receiving systems that shall give an indication of one type at resonance, and an indication of another and different type at 45 each side of resonance.

In carrying into effect the tuning indication operation of the control system in accordance with the invention, a phase discriminating network, in connection with tuned coupled high frequency circuits, is arranged to provide a control potential which is positive when the receiving system is tuned to one side of resonance, and negative when tuned to the other side, the magnitude of the potential increasing sharply as the 55 tuning is varied from the point of resonance.

It is also an object of the present invention to provide an accurate indication of resonance, without requiring the use of additional selective circuits even though the receiving system is arranged to pass a wide frequency band.

The invention will, however, be better understood from the following description when considered in connection with the accompanying drawing, and its scope will be pointed out in the appended claims.

In the drawings:

Figure 1 is a schematic circuit diagram of a tuning indication system embodying the invention;

Figure 2 is a modification of the circuit of Fig. 1, arranged to provide signal detection and amplification with automatic volume control in addition to tuning indication, and

Figure 3 is a modification of the circuit of Fig. 1 arranged to utilize radio frequency impulse 20 in the control of the indicating device.

Referring to Fig. 1, the rectangle 5 represents any suitable receiving system having tuning means represented at 6. In the present example, the receiving system may be considered as including a radio frequency amplifier, first detector and oscillator as indicated. The signal channel of the receiving system following the first detector comprises an intermediate frequency amplifier tube 7 connected with an intermediate frequency input transformer 8 and having an output circuit 13 coupled to the primary winding 10 of a second intermediate frequency coupling transformer 9. The secondary is divided into two equal winding sections 11 and 12, whereby it is 35 adapted to be connected into a phase discriminating network of the type shown, described and claimed in my copending application, Serial No. 134,105, filed March 31, 1937, for High frequency signal responsive control system, and assigned 40 to the same assignee as the present application, for deriving control potentials through a diode rectifier device 23.

As described in that application, in a control system which employs a phase discriminating 45 network as shown, a change in either the frequency of a received signal or a change in the tuning of the receiver is converted into a difference in phase between two voltages which are 50 then applied to the phase discriminating network. By utilizing the voltages which may appear across the primary and secondary of a coupled tuned circuit transformer, I have provided in one embodiment of my invention, a simple arrangement 55 for converting a change in tuning from resonance,

or a change in the frequency of a received signal, into a change in the phase relation between two alternating current voltages having the same frequency, and means for deriving control potentials from said change in phase relation.

The primary winding is tuned to the intermediate frequency by a shunt adjustable tuning capacitor 15, and the secondary is similarly tuned by a shunt adjustable tuning capacitor 16. The 10 tuned primary and secondary windings provide two coupled tuned circuits 17 and 18 resonant at the same frequency.

The windings 11 and 12 are arranged to form a continuous winding inductively coupled to the 15 winding 10 and the high potential or outer terminal ends thereof are connected to the secondary tuned circuit terminals, indicated at 19 and 20, and to the anode electrodes 21 and 22, respectively, of a rectifier device which is included 20 within a combined rectifier and amplifier tube indicated at 23.

The rectifier anodes 21 and 22 are associated with a common cathode 24 of the device 23 which cathode is connected through a lead 25 with the 25 tuned primary circuit 17. Continuing through the circuit 17 the anode connection includes the positive anode supply lead 14. The secondary winding sections are each connected with the lead 14 and a secondary center tap terminal 26 30 through two resistor sections 27 and 28. The latter are connected in series between the adjacent terminal ends of the secondary sections 11 and 12 through leads indicated at 29. The resistor sections are provided with intermediate 35 frequency bypass capacitors 30 and 31.

The signal or carrier potential applied between the cathode 24 and the center tap 26 of the output resistors 27 and 28, is derived from the primary or input circuit 17 through the connection 40 lead 25 between the cathode 24 and the high potential terminal 26A. The opposite side of the tuned primary winding is bypassed to the negative B supply terminal 42 and to ground 43 through the bypass capacitor 44. Likewise the center tap 26 is bypassed to ground through the lead 14 and the bypass capacitor 44. Direct current control potentials are derived from the resistor output terminals 32 and 33 through output leads indicated at 34 and 35.

50 In this circuit, advantage is taken of the fact that at resonance the primary and secondary voltages of the coupled tuned circuit intermediate frequency transformer are 90° out of phase with each other. By applying the signal or carrier voltage across the primary of the transformer between the cathode 24 and the resistor center tap 26, and the secondary signal or carrier voltage between the two diode anodes 21 and 22, the desired phase relations for the phase 55 discriminating network are obtained. If the frequency of the signal applied to the transformer is changed either because of a slight change in the tuning of the receiver, or a change in the frequency of the transmitter, the phase 60 relation between the primary and secondary voltages will change. A phase change of approximately 180° will be obtained between the primary and secondary voltages as the frequency of the signal applied to the transformer is varied 65 through the frequency range included within the resonance characteristic of the transformer.

When the signal applied to the intermediate frequency amplifier tube 1 is in resonance with the transformer feeding the double diode rectifier 23, a voltage will be applied between the 70

cathode 24 and the resistor center tap 26 which will be 90° out of phase with the voltage developed across the secondary coil sections 11 and 12 and applied between the anodes 21 and 22.

If only the voltage developed across the transformer primary is applied to the double diode between the cathode 24 and the resistor center tap 26, the rectified current flowing through the resistor section 27 will be equal and opposite in direction to that flowing through resistor section 28 and the voltage between the terminals 32 and 33 will be zero. Likewise if only the voltage developed across the secondary of the transformer is applied to the double diode rectifier between the anodes 21 and 22, the rectified current flowing through the resistor section 27 will be equal and opposite in direction to that flowing through resistor section 28 and the voltage between the terminals 32 and 33 will be zero.

If both the primary and secondary voltages are applied to the double diode and these voltages are 90° out of phase, as will be obtained if the signal applied to the transformer has the frequency to which the transformer is resonant, then the signal voltages applied to the two anodes 25 will still be equal and the rectified currents flowing through the two resistor sections will be equal and opposite and the voltage between terminals 32 and 33 will be zero.

If, however, the signal potential applied to the transformer has a frequency which differs slightly from the resonance frequency of the transformer, the phase relation between the primary and secondary voltages will no longer be 90° and the signal potentials applied to the two anodes 35 will not be equal and a difference in potential will exist between the terminals 32 and 33 because the rectified currents flowing through resistor sections 27 and 28 will be unequal.

Assuming that the applied signal has a frequency which is just inside the frequency response characteristic of the transformer, with a conventional intermediate frequency transformer this signal frequency would differ from the resonance frequency of the transformer by from 45 2 kc. to 5 kc. Under these conditions a phase difference of approximately 180° would exist between the primary and secondary voltage.

Assuming that with this phase difference, the voltages are such that the voltage applied to the anode 21 by the primary of the transformer is in phase with the voltage applied to this anode by the secondary of the transformer, the voltages applied to this anode will then add and if they are equal the anode signal potential will then be twice the value obtained when only the secondary voltage is applied to the double diode. This will cause a corresponding increase in the rectified current flowing through resistor 28. On the other hand the signal potentials applied to the anode 22 will be 180° out of phase and if they are equal in magnitude, the sum of the voltages on this anode will be zero. Therefore, no current will flow through resistor 27 and consequently no drop in potential will occur across 60 this resistor.

Since considerable current flows through resistor 28, a relatively large voltage will be developed across this resistor and this voltage will appear between the terminals 32 and 33. Since 70 the current causing this drop in potential must flow through the circuit comprising the resistor 28 and the anode 21 and cathode 24, the direction of the current will be such that the terminal 32 will be negative with respect to terminal 33. 75

If the frequency of the signal applied to the transformer feeding the double diode is changed so that it just falls within the other side of the transformer frequency response characteristic, the phase relation between the primary and secondary voltages will shift by approximately 180°. Under this condition, the large signal potential will be applied to the anode 22 while the signal potential on the anode 21 will be substantially zero. Considerable rectified current will now flow through resistor 27 and no current will flow through resistor 28. This current will flow through resistor 27 in such a direction that the resultant drop in potential across the resistor 15 causes the terminal 32 to become positive with respect to the terminal 33.

Thus, as the frequency of the signal applied to the transformer is varied through the frequency range corresponding to the transformer's frequency response characteristic, the potential across the terminals 32 and 33 will decrease from a given value, pass through zero, change polarity, and increase to the initial value again. This change in potential across terminals 32 and 33 as the frequency of the signal applied to the transformer is varied causes a large change in control potential to be made available for a small change in frequency.

While the tuning indication may be derived from any suitable portion of the signal channel of the receiver, the intermediate frequency amplifier is preferable for the reason that the latter operates at a fixed frequency and includes fixed tuned circuits at the various interstage transformers.

In an intermediate frequency amplifier, therefore, a pair of coupled tuned circuits already existing in the signal channel of the receiver and operating at the same frequency may be used to derive two potentials at the same frequency, having a phase relation which varies as the signal applied thereto tends to vary on either side of the predetermined intermediate frequency.

Thus, there may be established in an intermediate frequency amplifier, a phase discriminating network which provides a differential direct current voltage which varies in magnitude and polarity as the frequency of the received signal varies above or below resonance. By connecting a polarized indicating device or other suitable indicating device responsive to changes in polarity and voltage magnitude to the output leads 34 and 35, tuning indication may readily be obtained, which is sharply responsive to changes in tuning and which gives a certain indication at resonance and a different type of indication on either side of resonance. By this means, the operator of a receiver may readily determine in which direction changes in tuning are to be made to correct for off-resonance tuning and to bring the receiver directly into resonance with a received signal.

A tuning indicator means adapted for control by potentials derived from the phase discriminator network is a cathode ray tube 37 having electron emitting means 38, deflecting plates 39, which plates are connected with the leads 34 and 35 as indicated, to control the cathode ray beam on the screen indicated at 41.

If this voltage is applied to the electrostatic deflector plates of a cathode ray tube, as shown, the cathode ray beam may be adjusted to provide a figure or pattern on the screen 41 which will change with changes in the magnitude and polarity of the applied control voltages. When res-

onance is obtained, the figure may be a circle or spot in the center of the tube and, for off-resonance condition, may change to an ellipse formed on one side or the other of the tube, thereby producing one form of indication for resonance and a differing indication for off-resonance tuning, whereby the indication permits the direction of tuning to be determined for correcting the off-resonance condition as well as indicating the exact resonance point.

In the tuning indicator system shown, the primary or anode circuit is returned to the center tap of the resistors 27 and 28 and the cathode is connected therewith through the primary so that the rectifier circuit is at anode B potential. This circuit arrangement permits the deflector plates to operate at positive B potential with direct connection with the output resistors 27 and 28.

If the device 23 in which the rectifier elements are provided is also a double diode triode tube as indicated, having a control grid 45 and an output anode 46, the device may be arranged to provide automatic volume control bias by connecting a resistor 47 between the control grid 45 and lead 14 and connecting an automatic volume control lead 49 to the grid end of resistor 47, as shown. With this arrangement, the primary voltage is rectified by the diode rectifier action of the tube in which the grid acts as an anode of the rectifier. A suitable intermediate frequency bypass capacitor 50a is provided across the automatic volume control resistor 47. Signal output potentials may then be derived from the secondary circuit between the terminal 26 and the terminal 32. Audio frequency or modulation potentials may be derived from the resistor 47. The value of the capacitor 50a should be such that it provides an effective bypass at intermediate frequencies without appreciably attenuating the audio frequency potentials in the desired range of operation.

A circuit for deriving signal potentials and automatic volume control potentials is also shown in Fig. 2, to which attention is now directed. In Fig. 2, like parts as in Fig. 1 are designated by the same reference numerals.

In the present example, the double diode rectifier is provided by a tube 50 which may be of the type known as an RCA 6H6 having two anode electrodes 51 and 52 each associated with a cathode 53. The anodes 51 and 52 are connected with the terminals 19 and 20 of the tuned secondary circuit 18 which comprises the secondary winding sections 11 and 12 and the shunt tuning capacitor 16. The resistor sections 21 and 28 are included serially between the secondary windings. Output leads 34 and 35 are connected with output terminals 32 and 33 on the resistors and the latter are provided with bypass capacitors 30 and 31.

The center tap 26 on the resistor elements is connected with the cathode 53 through a lead 54 and a coupling resistor 55. The output anode circuit 13 of the amplifier 7 is connected with the primary winding 10 which is provided with a shunt variable tuning capacitor 15 to form the tuned primary circuit 17, and the latter is coupled to the cathode 53 through a coupling capacitor 56 in conjunction with the coupling resistor 55 which forms a coupling resistor. Since the secondary circuit is conductively isolated by the coupling capacitor 56, the secondary circuit may be grounded at any suitable point as at the terminal 32 as indicated by the ground connection 58.

The operation of the circuit of Fig. 2 is similar to that of Fig. 1 and the tuning indicator device is connected with the output resistor comprising the sections 27 and 28 in a similar manner to the cathode ray tube of Fig. 1.

In the present example, the tuning indicator device is an electrical meter indicated at 71 having a movable pointer 72 which moves over an indicating scale 73 on either side of a zero position in which it is shown at 74.

The meter is connected to the leads 34 and 35 to receive the differential potential from the output resistor 27-28 and the indicator moves to the right or left as the potential increases from zero 15 in either direction depending upon the polarity of the terminals 32 and 33, one with respect to the other.

The derivation of the variable potential is the same as in the circuit of Fig. 1 except that the 20 cathodes 53 are conductively connected back to the center tap 26 through the primary circuit by way of the coupling resistor 55 with which the primary is coupled in shunt relation through the coupling capacitor 56, thereby permitting grounding of the secondary circuit. A choke coil may be substituted for the resistor 55 if desired.

Any suitable polarized indicating device may be used in connection with the leads 34 and 35 to respond to the signal variable potential.

30 The circuit has the advantage that the modulation or audio frequency component of the received signals may be applied to an output amplifying circuit through a second detector comprising a diode rectifier 59 connected with one-half of the secondary winding. In the present example, a cathode 60 is connected with the terminal 20 of the tuned circuit 18, and the anode electrode 61 is connected through an output resistor 62 for the detector, to a ground lead 63 connected to the terminal 32. The output resistor is provided with a suitable by-pass capacitor 64.

The intermediate frequency carrier wave received in the tuned circuit 18 is applied in part to the rectifier 59 across one-half of the secondary winding 12, and the modulation and direct current component thereof appear across the output resistor 62.

50 The output resistor 62 may be connected between the control grid 65 and the cathode 66 of an audio frequency amplifier 67 to apply a biasing potential thereto and audio frequency signals simultaneously, whereby the amplifier is diode biased by the signal. The audio frequency output is derived from an output lead 68 in connection with the output anode 69. The cathode 66 is connected with the ground lead 63, as indicated. Automatic volume control potentials may be derived from the output resistor 62 through an output lead indicated at 70 and applied to any 55 suitable portion of the receiving system for automatic volume control purposes, in any well-known manner.

In the embodiment of my invention illustrated in Fig. 3, the radio frequency potentials developed across the primary and secondary of transformer 9 are applied directly to the deflecting plates 39' and 40 of the cathode ray tube 37 and the rectifier tubes used with the arrangements shown in Figs. 1 and 2 are eliminated. By applying the voltage across the primary of transformer 9 to the vertical deflecting plates and the voltage across the secondary to the horizontal deflecting plates a circle will be formed on the screen of the cathode ray tube when the applied signal has the frequency to which the trans-

former is resonant and provided that the voltages applied to the two sets of deflecting plates are substantially equal. If the frequency of the applied signal is varied on either side of the frequency to which the transformer is tuned the figure on the screen of the cathode ray tube will change from a circle to an ellipse the inclination of which will indicate whether the frequency of the applied signal is above or below the frequency to which the transformer is tuned. In 10 this embodiment resistors 27 and 28 and by-pass condensers 30 and 31 can be eliminated so that a single coil can be substituted for windings 11 and 12.

While the tuning indication system has been 15 shown and described in connection with an intermediate frequency amplifier, it may be applied to other portions of the radio receiving system wherein two circuits are provided which operate at the same signal frequency and which 20 provide signal voltages which vary in phase in response to off-resonance tuning. However, for reasons which have hereinbefore been pointed out, the tuning indication system is at present preferred in connection with the intermediate 25 frequency amplifier, since this connection permits existing apparatus to be utilized to advantage.

I claim as my invention:

1. In a radio signal receiving system, the combination of means for tuning said system to resonance with a received signal, means providing two substantially equal signal potentials in response to a received signal, said potentials having the same frequency and a predetermined phase 30 relation to each other when said receiving system is adjusted to resonance with said received signal, means for converting a variation in frequency of said received signal into a variation in phase between said potentials, said first and second-named means including the primary and secondary of a coupled tuned circuit intermediate frequency transformer through which said received signal is conveyed, means for converting said variation in phase into a controlling potential for said system, said controlling potential being variable in response to said phase variation in magnitude and direction of variation from a zero value, indicating means responsive to changes in the magnitude and direction of variation of said potential, whereby resonance and off-resonance conditions of tuning of said system are provided thereby, a signal rectifier connected with said first-named means for rectifying at least a portion of one of said signal potentials, 50 and means for deriving the modulation component of said signal and automatic volume control potentials from said last-named rectifying means.

2. In a superheterodyne receiver, the combination with tuning means therefor, of an intermediate frequency amplifier, a coupling transformer for said amplifier having a tuned primary circuit and a tuned secondary circuit resonant at the same intermediate frequency, said secondary winding having two tuning inductance sections, 65 a resistor element having a center tap connected between said sections, a rectifier device having a cathode and two anode electrodes associated therewith, said anode electrodes being connected with the terminals of said secondary circuit and 70 said cathode being connected through the primary circuit with said center tap on the resistor element, means for deriving differential direct current potential from said resistor element in response to received signals, tuning indication 75

means responsive to the magnitude and polarity of said potential connected with said resistor element, and means for deriving audio frequency signal and automatic volume control potentials from at least one portion of said secondary circuit.

3. In a radio receiving system, the combination with means for tuning said system to resonance with a signal, of a signal amplifier provided with two tuned coupled signal conveying circuits, said circuits being resonant at substantially the same signal frequency, said tuned circuits including the primary and secondary windings of a tuned transformer device, a rectifier having a cathode connected through the primary winding with a center tap on the secondary winding and having a pair of rectifier anode electrodes connected with the terminals of the secondary windings, an output resistor for said rectifier, a cathode ray indicating device having a pair of beam deflecting electrodes connected with said output resistor, an audio frequency detector connected with one of said windings, and means for deriving audio fre-

quency and automatic volume control potentials from said last named detector.

4. In a superheterodyne receiving system, the combination with an intermediate frequency amplifier, of an interstage coupling transformer therefor having a tuned primary and a tuned secondary winding responsive to the same intermediate frequency, a pair of resistors interposed in the secondary providing a center tap therefor, a rectifier having a cathode connected through said primary winding with said center tap and having a pair of anodes connected with the terminals of the secondary, a cathode ray indicating tube having at least one pair of beam deflecting electrodes connected with one of said windings to receive a differential controlling potential therefrom responsive to a variation in frequency of a signal, a rectifier device connected with a portion of the secondary winding and having an output resistor, and an audio frequency amplifier connected with said resistor to receive output signals therefrom

GEORGE L. BEERS.
